1

This invention relates to drilling machines of the kind in which an abrasive medium is applied to the contoured drilling point of a drill. Such machines are for example used for drilling diamonds for use as wire drawing dies. In such machines, the drilling tool is in the form of a rapidly rotating drill, e. g. a steel needle, the point of which is given the configuration which is desired in the finished hole and which is charged with an abrasive, such as oil containing diamond dust. The drilling operation is performed by axially reciprocating the support carrying the work so as to bring the latter into and out of engagement with the rotating drill or needle. Owing to the wear to which the drill is subjected, it needs to be restored to shape at comparatively frequent intervals, by the use of a rotating grinding or lapping wheel. During this re-shaping operation the work support has to be retracted from its normal working position so that the grinding wheel has free access to the point of the drill.

According to the present invention for restoring the shape of the drill of a drilling machine of the kind referred to, comprising a rotating drill and a reciprocating work support, the work support is mechanically retracted and the grinding or lapping wheel is mechanically advanced to engage the drill, both mechanical movements being derived from the main drive of the machine. Preferably a cam shaft is provided which is driven from the main drive. This cam shaft carries two cams, one of which effects the retraction of the work support, and the other of which effects the advance of the grinding wheel. Advantageously the work support is spring urged towards the drill and the reciprocation is effected by means of a cam operated rocking lever which engages a projection on the work support. With this arrangement the retraction necessary for the operation of restoring the shape of the drill can be occasioned by imparting an additional displacement to the rocking lever.

Existing drilling machines of this kind and comprising a rotating drill and a reciprocating work support can readily be converted into machines in accordance with the present invention by the incorporation of an attachment comprising a cam shaft with suitable gearing for driving the cam shaft from the main drive of the machine, the cam shaft being provided with two cams, one of which engages a rocking lever adapted to impart movement to the work support to retract it from the drill and the other cam engaging a second rocking lever mounted to

2

engage a support for the grinding wheel to advance the latter towards the drill.

In arrangements according to the present invention, it is preferred to employ a grinding or lapping wheel of cylindrical form mounted with its axis in a plane at right angles to the axis of the drill, but for some purposes it may be desirable to dispose the grinding wheel with its axis parallel with or inclined to the axis of the drill, and/or to use a non-cylindrical wheel.

In order that the invention may be more readily understood reference will now be had to the accompanying drawings which show a preferred constructional form of a machine for drilling diamonds for use as wire drawing dies and in which

Fig. 1 is a side elevation of the machine.

Fig. 2 is a plan view.

Fig. 3 is a perspective view from the side opposite to Fig. 1.

Fig. 4 is a detail view substantially on the line IV—IV of Fig. 1.

Fig. 5 is a perspective view of part of Fig. 1.

The drill or needle 1 (Fig. 1) is mounted in 25 a chuck 2 carried on a shaft 3 which is journalled in bearings 4 in bracket members 7 integral with the main frame of the machine. The bearings 4 have to be precisely aligned and adjusted so that the drill 1 rotates precisely about its own 30 axis without detectable lateral movement. The spindle 3 is driven by way of a pulley 5 and a driving cord 6 passing over the pulley 5 and round a driving pulley (not shown). The diamond 8 (Fig. 2) which is to be drilled to form 35 the wire drawing die is mounted on a support 9, which is carried in grooved rollers 10, rotatably supported on bearing pins 11. The bearing pins 11 have to be adjusted to permit free rotation of the rollers 10 with their grooved surfaces in 40 precise alignment and without detectable lateral movement. The mount 12 carrying the pins 11 and the rollers 10 is supported on the main frame of the machine by means of levelling screws 13 (Fig. 1), and is locked by means of lateral adjusting screws 14. By means of the screws 13 and 14 the mount 12 can be adjusted so that the diamond support 9 moves precisely in axial alignment with the drill 1. Engaging a clip 15 on the 45 rear end of the diamond support 9 is a spring 16, which tends to urge the diamond 8 towards the drill 1. The other end of the spring 16 is secured in an anchor 17, which is adjustably mounted on a rod 18 to which it is clamped by a spring clamp 19. By adjusting the position of the anchor 17 lengthwise of the rod 18 the ten-

sion of the spring can be varied. The diamond support 9 carries a downwardly projecting pin 20 (Fig. 2) which engages in a slot 21 (Fig. 3) formed in the mount 12 (Fig. 2). The co-operation of pin 20 (Fig. 3) and slot 21 prevents rotation of the diamond mount 9 during the drilling operation without impeding the free movement of the diamond support in the axial direction.

The reciprocation of the diamond support 9 in the axial direction during the drilling operation is occasioned by means of a rocking lever 22 one end of which engages the pin 20 so as to move the diamond support 9 away from the drill 1 against the action of the spring 16. The movement of the lever 22 is so controlled that in its forward position it is clear of the pin 20, so that the diamond 8 is held against the drill 1 by the action of the spring 16. The lever 22 is mounted on a pivot pin 23 (Fig. 4) which is substantially vertical and in the construction shown has conical bearing ends received by adjustable centres 24. By careful adjustment of the centres 24 the pivot pin 23 can be set to rotate freely without lateral movement. The lever 22 (Fig. 5) is provided at the end remote from the pin 20 with a pivoted section 25 which is urged upwardly by means of a spring against an adjusting screw 26. The free end of the lever section 25 carries screw 27 which is adjustable and which has a hardened point engaging the hardened surface of a face cam 28. This cam 28 is carried on a shaft 29 journaled in a bearing bracket 30 and also carrying a stepped pulley 31 enabling the cam 28 to be rotated by a driving belt 32. The spring 33 (Fig. 4 and Fig. 5) is anchored in one of the centres 24 engages the pin 23 and acts in such manner as to tend to hold the pin 27 in engagement with the face cam 28. The same spring 33 also passes round an adjusting screw 34 (the purpose of which will be described below), and its free end passes round the pin 27 to constitute the spring urging the lever section 25 upwardly. The engagement of the spring with the screws 27 and 34 also serves to lock these screws against undesired movement. During the rotation of the face cam 28 (Fig. 2) the pin 27 causes the lever 22 to pivot about the pin 23 and consequently equivalent movement is imparted by way of the pin 20 to the diamond support 9. By means of the adjusting screw 26 (Fig. 4 and Fig. 5) the distance of the pin 27 from the centre of the cam 28 can be adjusted with corresponding adjustment of the throw of the lever 22. In this way the diamond support 9 is continuously oscillated towards and away from the drill 1 so that the drilling operation can take place in the desired manner. The bracket 30 (Fig. 1) and the carrier for the centres 24 (Fig. 4) are both mounted at the free end of a bifurcated lever 35 which is pivotally mounted on a shaft 36 (Fig. 1). The shaft 36 is secured in a fixed quadrant 37 (Fig. 4) which is bolted to the main frame by means of bolts 38. The arm 35 is secured in the desired position by means of a clamping bolt 39 passing through an arcuate slot in the quadrant 37. In this way the mechanism for reciprocating the diamond support 9 can be adjusted in relation to the diamond support and can also, if desired, be pivoted into an inoperative position in which the clamping bolt 39 occupies the outer end of the slot in the quadrant 37.

Owing to the wear to which the point of the drill 1 is subjected during the drilling operation,

it is necessary to be able to restore the shape of the point of the drill periodically. The mechanism for retracting the diamond support 9 to enable the re-shaping to be performed and for advancing the grinding or lapping wheel which is to perform the re-shaping operation will now be described.

Mounted on the pivotal assembly constituted by the arm 35 (Fig. 4 and Fig. 5) and the bracket 30 is a transverse shaft 40 which has a rigidly attached upwardly extending arm 41 which engages the end of the previously mentioned screw 34. Also rigidly attached to the shaft 40 is a downwardly extending arm 42, the extremity of which is adapted to engage the face cam 48 (Fig. 1). The shaft 40 (Fig. 4) is associated with a spring 43 tending to hold the lever 41 out of engagement with the pin 34. The face cam 48 (Fig. 1 and Fig. 5) is carried on a cam shaft 44 which is journalled in bearings 45 carried in supporting brackets 46. The cam shaft is driven by means of a driving chain 47 which also passes over a driving wheel (not shown) driven from the main drive by way of a suitable reduction gear. In the rotation of the cam shaft 44 the face cam 48 engages the arm 42 thereby rocking the shaft 40 (Fig. 4 and Fig. 5) so as to bring the lever 41 into engagement with the adjustable screw 34 to pivot the lever 22 on its pivot pin 23, whereby due to the engagement of the lever 22 with the pin 20 the diamond support 9 is retracted clear from the drill 1. Simultaneously the end of the adjustable screw 27 is lifted out of engagement with the face cam 28 so that the normal reciprocating movement is suspended. This position is shown in Figs. 1 and 2 of the drawings. When the diamond support 9 is in this retracted position the re-shaping operation can be performed on the drill 1. For this purpose the cam shaft 44 (Fig. 1 and Fig. 5) carries a second cam 49 which is a radial cam and which is engaged by a transversely extending cam lever 50. This lever is pivoted between its ends on a pivot 51, and the end remote from the cam 49 engages the lower end of a vertical column 52 which is slidably in a guide 53. In the rotation of the cam 49 the lever 50 is rocked with consequent vertical movement of the column 52. Clamped to the upper end of the column 52 (Fig. 3) by means of a clamp 54 is a fork 55 carrying the grinding or lapping cylinder 56. The fork 55 is preferably pivotally mounted to the upper end of the column 52 so that it can be adjusted in relation to the end 55 of the drill 1. By means of the clamp 54 the fork 55 is firmly secured in the desired position. The lapping cylinder 56 (Fig. 2) is secured on a shaft 58 which also carries a driving pulley 57. The ends of the shaft 58 are in the form of cones running in centres 59. These bearings have to be adjusted with great precision so as to obtain free rotation without lateral movement. The driving pulley 57 is engaged by a driving belt 60 which is driven from a suitable driving pulley (not shown). Preferably the driving pulley is provided with deep flanges so that when the column 52 is in its lower-most position the driving belt 60 is slack but still retained within the deep flanges. When the column 52 is moved upwardly to bring the lapping wheel 56 into engagement with the drill 1 the driving belt 60 is tightened and the desired drive is imparted to the shaft 58.

With the re-shaping arrangements as described, the wear on the cylinder 56 is located

substantially at one point. It is therefore desirable that provision should be made for bringing different parts of the lapping cylinder 56 into the operative position. In the arrangement as shown this can be done by adjusting the centres 59 in which the shaft 58 runs. The lapping cylinder 56 can conveniently take the form of a copper cylinder in the surface on which diamond dust is embedded.

In the construction as hereinbefore described with reference to the drawings, adjustment of the cylinder 56 (Fig. 1) in the axial direction of the drill 1 is achieved by pivotal adjustment of the fork 55 in relation to the column 52, the fork being secured in adjusted position by the clamp 54.

The perspective view of Fig. 3 shows the relative positions of the different parts of the apparatus during the actual engagement of the lapping wheel 56 with the drill 1. The timing of the cams 48 and 49 is such that the diamond support 9 is first retracted, then the lapping wheel 56 is advanced to perform the re-shaping operation, the lapping wheel 56 is then withdrawn and finally the diamond support 9 is released again so that it can advance into the position in which the normal oscillatory movement for the drilling operation is derived from the cam 28.

In the apparatus as shown in the accompanying drawings the arrangement of the drill 1 and of the diamond support 9 and its mount 12 in relation to the main frame of the machine, is in accordance with existing arrangements. It is, therefore, apparent that an existing machine can readily be modified by the provision of the cam shaft 44 and the lever mechanism associated therewith for retracting the diamond support and for advancing the lapping cylinder. The arrangement for oscillating the diamond support as described and shown is particularly advantageous in a machine according to the present invention, as it enables the same lever which operates the oscillatory movement to be used for the retraction which is necessary for the re-shaping operation. In existing machines, however, it might be preferred to retain existing mechanisms for performing the oscillatory movement and to utilize only that part of the mechanism shown which serves for the retraction of the diamond support and for the control of the lapping cylinder.

We claim:

1. A drilling machine of the type in which an abrasive medium is applied to the contoured drilling point of a drill, comprising a rotatable drill, means to rotate said drill from a main drive of the machine, a work-supporting member arranged in alignment with the axis of the drill, means actuated by the main drive for reciprocating said work-supporting member axially of the drill during the drilling of the work, a rotatable shaping tool for refinishing the point of said drill, and means for retracting the work-supporting member along the axis of the said drill from the drilling position and simultaneously disengaging the work-supporting member from the said reciprocating means and advancing the said rotatable reshaping tool into engagement with the drill, said means comprising a cam element rotated by the main drive, a rocking lever actuated by said cam element and coupled to said work-supporting member and controlling the position of said work-supporting member independent of said reciprocating means, and an ad-

justable supporting member for said rotatable shaping tool coupled to said cam element.

2. A drilling machine of the type in which an abrasive medium is applied to the contoured drilling point of a drill comprising a rotatable drill, means to rotate said drill from a main drive of the machine, a work-supporting member arranged in alignment with the axis of the drill, means actuated by the main drive and including a rocking element for reciprocating said work-supporting member axially of the drill during the drilling of the work, a rotatable shaping tool for refinishing the point of said drill, a cam shaft, a pair of cams on said shaft, means for driving the cam shaft from the main drive of the machine, a follower cooperating with one of said cams, a lever actuated by said follower for displacing said rocking element of said work-supporting member reciprocating means, a second follower cooperating with the other of said cams to advance said shaping tool into engagement with the drill during the displacement of the work support by the said rocking element, and means for driving said shaping tool.

25 3. A drilling machine of the type in which an abrasive medium is applied to the contoured drilling point of a drill, comprising a rotatable drill, means to rotate said drill from a main drive of the machine, a work-supporting member in alignment with the axis of the drill, means to reciprocate said work-supporting member axially of the drill during the drilling, said means comprising a spring member for displacing said work supporting member towards the drill, a rocking element in engagement with said work-supporting member for moving said work-supporting member against the spring action, and a cam driven from the main drive of the machine and engaging said rocking element, a rotatable shaping tool for refinishing the point of said drill, a cam shaft, a pair of cams on said shaft, means for driving the cam shaft from the main drive of the machine, a follower cooperating with one of said cams and displacing the said rocking element from the cam reciprocating the said work-supporting member, a second follower cooperating with the other of said cams to advance said shaping tool into engagement with the drill when the work-supporting member is displaced by the said rocking element, and means for driving said shaping tool.

4. A drilling machine of the type in which an abrasive medium is applied to the contoured drilling point of a drill, comprising a rotatable drill, means to rotate said drill from a main drive of the machine, a work-supporting member in alignment with the axis of the drill, means to reciprocate said work-supporting member axially of the drill during the drilling, said means comprising a spring member for displacing said work-supporting member towards the drill, a rocking element in engagement with said work-supporting member for moving said work-supporting member against the spring action, and a cam driven from the main drive of the machine and engaging said rocking element, a drill reshaping tool comprising a grinding cylinder adjustably mounted with its axis in a plane at right angles to the axis of the drill, a cam shaft, a pair of cams on said shaft, means for driving the cam shaft from the main drive of the machine, a follower cooperating with one of said cams and displacing the said rocking element from the cam reciprocating the said work-supporting member, a second follower cooperating

with the other of said cams to advance said shaping tool into engagement with the drill when the work-supporting member is displaced by the said rocking element, and means for driving said shaping tool.

5. In a drilling machine having a work support reciprocated by a cam and a lever pivoted perpendicular to the axis of the cam, means for varying the length and end positions of the stroke of the lever comprising a hinge member having an end pivoted on the lever at a point intermediate the ends of the lever and at right angles to the pivot of the lever, an adjusting screw passing through the lever and engaging the hinge member for adjusting the angle between the lever and the hinge member, and an adjusting

screw passing through the hinge member at right angles to the axis of the said first screw and engaging the surface of said cam.
